FIG. 4 is a rear elevational view of a first embodiment
thereof;FIG. 5 is a bottom plan view of a first embodiment thereof;
FIG. 6 is a top plan view of a second embodiment thereof;
andFIG. 7 is a front elevational view of a second embodiment
thereof;FIG. 8 is a side elevational view of a second embodiment
thereof;FIG. 9 is a rear elevational view of a second embodiment
thereof; andFIG. 10 is a bottom plan view of a second embodiment
thereof;FIG. 11 is a top plan view of a third embodiment thereof;
FIG. 12 is a front elevational view of a third embodiment
thereof;FIG. 13 is a side elevational view of a third embodiment
thereof;FIG. 14 is a rear elevational view of a third embodiment thereof; and

FIG. 15 is a bottom plan view of a third embodiment thereof;

FIG. 16 is a top plan view of a fourth embodiment thereof;

FIG. 17 is a front elevational view of a fourth embodiment thereof;

FIG. 18 is a side elevational view of a fourth embodiment thereof;

FIG. 19 is a rear elevational view of a fourth embodiment thereof; and

FIG. 20 is a bottom plan view of a fourth embodiment thereof;

FIG. 21 is a top plan view of a fifth embodiment thereof;

FIG. 22 is a front elevational view of a fifth embodiment thereof;

FIG. 23 is a side elevational view of a fifth embodiment thereof;

FIG. 24 is a rear elevational view of a fifth embodiment thereof; and

FIG. 25 is a bottom plan view of a fifth embodiment thereof. It being understood that the broken line indicates that the design continues uniformly for an indefinite length.
